UNITED STATES PATENT OFFICE.

HARRY P. SPEER, OF COUNCIL BLUFFS, IOWA, ASSIGNOR OF ONE-HALF TO JOHN M. WHEELER, OF COUNCIL BLUFFS, IOWA.

RAILROAD COUPLER ATTACHMENT.

Application filed November 9, 1927. Serial No. 232,057.

The present invention relates to an attachment for a railroad coupler and has for its prime object to provide means for opening the knuckle and holding the knuckle of the coupler open until the coupling is desired to be made.

Other very important objects of the invention reside in the provision of an attachment of this nature which is exceedingly simple 10 in its construction, strong and durable, inexpensive to manufacture, thoroughly efficient and reliable in operation, and otherwise well adapted to the purpose for which it is designed.

With the above and numerous other objects in view as will appear as the description proceeds, the invention resides in certain novel features of construction, and in the combination and arrangement of parts as 20 will be hereinafter more fully described and claimed.

In the drawing:

Figure 1 is a plan view of my attachment on a coupler,

25 Figure 2 is a side elevation thereof,

Figure 3 is an enlarged detail section through a portion of the attachment taken substantially on the line 3—3 of Figure 1, and

30 Figure 4 is a perspective view showing a rod and crank disconnected,

Figure 5 is a perspective view of an arm forming a part of the invention.

Referring to the drawing in detail it will be seen that the numeral 10 denotes a conventional coupler including the knuckle 11 and knuckle pin 12. The numeral 1 denotes a plate disposed on one side of the coupler 10 by means of the knuckle pin 12 projecting through an opening therein. This plate at 40 its rear lower corner is provided with an apertured ear 13 in which is disposed an eye bolt 2. The upper front corner of the plate 1 is provided with a bearing 14 in which is rotatable a shaft 15 formed integrally on one end of an arm 4 to project laterally therefrom. This shaft 15 has its end portion squared as at 16 to be received in a square opening 17 of a crank 18. This crank 18 has a reduced apertured end 19 to be received 50 between apertured ears 20 of a head 21 on a stem 22 and a pivot pin 23 extends through

the openings of the end 19 and the ears 20 for hingedly connecting the crank with the stem 22. This stem 22 extends through the eye of the eye bolt 2 and has a spring 3 coiled 55 thereabout impinging against the eye bolt 2 and against the head 21. The stop pin 25 is disposed through the end of the stem 22 as clearly shown in Figures 1 and 2. The arm 4 is provided with an arcuate notch 26 which 60 receives the projecting end 27 of a pin 28 extending through the knuckle 11. It will be seen that the spring urges the arm 4 to swing thereby tending to open or maintain in an open position the knuckle 11.

When the lock block in the coupler is lifted to release the knuckle, it throws the arm 4 out of lock and it automatically kicks open the knuckle and locks it open until the impact of another car forces the coupling, although 70 the knuckle can be closed by hand with little effort. Thus the parts do not interfere with the operation of the conventional coupler structure.

It is thought that the construction, operation and advantages of the invention will now be quite apparent without a more detailed description thereof. The present embodiment of the invention has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. An attachment for a coupler comprising a plate, means for attaching the plate to a coupler body, a rod for engagement with the knuckle of the coupler body to project 95 laterally from one side thereof, an eye member on the plate, a rod slidable through the eye member, a crank pivotally engaged with the rod, a shaft journaled in the plate and rotatable by the crank, an arm extending 100 from the shaft and having a notch to receive the rod in the knuckle.

2. An attachment for a coupler comprising a plate, means for attaching the plate to the side of the coupler, an apertured ear at the rear lower corner of the plate, a bearing at the upper front corner of the plate, an eye bolt in the apertured ear, a stem slideable through the eye bolt, a shaft journaled in the bearing and having an arm formed thereon, said shaft formed with a squared portion, a

crank having a squared opening receiving the squared portion, means pivotally engaging the crank with the stem and a spring on the stem urging the crank in one direction, said arm having a notch, a rod for insertion in an opening of a knuckle of the coupler and projecting in the notch. 10 15

In testimony whereof I affix my signature.
HARRY P. SPEER.
